UNITED STATES PATENT OFFICE

FRANCIS J. LEEAK, OF LANSING, MICHIGAN

PISTON SALVAGING DEVICE

Application filed November 7, 1931. Serial No. 573,638.

This invention relates to piston accessories for internal combustion engines, steam engines, air compressors and the like and has for its object an accessory in the nature of a piston salvaging device whereby the diameter of the piston may be increased in size to conform to the wear or reboring of the cylinder at no great expense to the owner. A further object is to provide an accessory for this purpose that is simple to install and easy to replace. A further object is to increase the wearing properties of the piston, for as the preferred form is to be constructed of brass, it is well known by those skilled in the art that brass against steel or a soft metal against a hard metal has much longer wearing qualities than two hard metals one against the other.

These and other objects will be more clearly brought out in the drawing, specification and claims.

In the accompanying drawing, which illustrates the invention, the characters indicate like parts throughout the several views.

Referring to the drawing:

Fig. 1 is a side elevation of a piston embodying my present invention.

Fig. 2 is a horizontal transverse sectional view taken on line 2—2 of Fig. 1 illustrating the application of the device.

Fig. 3 is a sectional view of the piston taken on line 3—3 of Fig. 1 and Fig. 2 illustrating the manner of turning the upper and lower ends of the device to eliminate sharp edges from coming in contact with the walls of the cylinder.

Fig. 4 is a perspective view of the device showing the anchor holes and one shape the device may take, such as tapered sides.

Fig. 5 is a perspective view of a modification of the invention having straight sides.

Referring to the drawing, numeral 1 is used to designate my invention as a piston saving device which may be applied to any of the present make of pistons. Its construction is a sheet of metal (preferably brass) of the desired thickness and shape in which there are a plurality of countersunk portions 2 in which there are holes 3 through which rivets 4 may pass.

Holes 6 are drilled and countersunk into piston 5 in position to correspond with those in my invention through which rivets 4 may pass. These rivets are then clinched to hold the device firmly in place. After the rivets 4 have been properly clinched on the inside of said piston 5 the top and bottom of said device 1 are turned over as shown at 7 and 8 thus making it more rigid and at the same time protecting the walls of the cylinder 60 from sharp edges. 55

With the foregoing description it will be readily understood that this device is an accessory to be used to reduce the play between the pistons and cylinders caused from wear 65 or reboring of the cylinder.

Its shape and thickness depends on the shape of the piston and corresponding size of the cylinder. It may be applied to one or both sides of the piston and may be secured thereto by rivets, screws, or bolts. The object is to provide an accessory to rebuild one or both sides of a piston to take up the play between said piston and the cylinder walls due to wear, grinding or reboring of the cylinder. To restore old pistons to their original diameter. 70 75

It will also be understood that my preferred form of this device will not score the cylinder on the side the device is applied. 80

Having now described my invention what I claim as new and novel is:—

1. In combination with a cylinder and co-operating piston therein, a piston salvaging device consisting of a thin sheet of metal having a plurality of countersunk portions said portions having transverse openings at their apex by means of which the device is securely fastened to the piston. 85

2. In combination with a cylinder and co-operating piston therein, a piston salvaging device consisting of a thin sheet of metal having a plurality of countersunk portions, said portions having transverse openings at their apex, said piston being provided with a plurality of countersunk holes with transverse openings at their apex to correspond with those in the salvaging device in which rivets, screws, or bolts are inserted to securely anchor 100 90 95

said salvaging device to the skirt of the piston.

3. In combination with a cylinder and co-operating piston therein a piston salvaging device consisting of a thin sheet of metal having a plurality of countersunk portions, said portions having transverse openings at their apex, said piston being provided with a plurality of countersunk holes with transverse openings at their apex to correspond with those in the salvaging device in which rivets, screws, or bolts are inserted to securely anchor said salvaging device to the skirt of the piston, said salvaging device having top and bottom edge's turned in toward the center of the piston to present a rounded edge toward the walls of the cylinder substantially as shown in Fig. 3.

In testimony whereof, I affix my signature.

20
